UNITED STATES PATENT OFFICE

ADOLPH W. MACHLET, OF ELIZABETH, NEW JERSEY

BRASS-MELTING APPARATUS

Application filed July 10, 1929. Serial No. 377,105.

This invention relates to improved means for melting brass.

Since the melting point of brass is extremely high, and since in order to make satisfactory brass castings it is necessary to superheat the melted brass to about 2100° or 2200° so that it can be poured satisfactorily, it has been customary to use melting pots formed of a composition of graphite or clay.

10 These materials are poor conductors, and the cost of fuel mounts very high.

In aiming to economize heat, it has been the practice to employ many different sizes and forms of pots, for melting different 15 quantities of brass, always using the smallest possible crucible for the work in hand. The crucible soon perishes from exposure to the extreme heat.

If it is sought to melt the brass in an ordinary pot of metal, it is found that it cannot withstand high heat as successfully as a graphite crucible, and the danger is incurred that superheating of the brass in the metal pot would result in melting the 25 metal pot itself. However, a metal pot or crucible is a desideratum because of its high conductivity and economy in fuel. According to the present invention, the brass is melted and superheated with less than half the expenditure of fuel than is necessary when using a graphite crucible. The difficulty and danger of melting the metal pot may be avoided by employing for the pot a certain 30 metal tube having ends of recalcitrant material, and keeping the tube in steady, slow revolution, so that it cannot become over-exposed to heat at any point, thereby avoiding melting or softening of the tube. The crucible may be made in the form of a barrel,

35 bottle or hollow cylinder, which may extend in cumbent position for convenience in charging and discharging; and the heat may be applied to the heat-absorbing top of the tube or barrel, remote from the work therein, whereby the top becomes very readily heated and upon revolution reaches a bottom position, where it contacts with the deposited metal therein and melts the same. Owing to the conductivity of the bottle, brass melting is 40 effected economically. The crucible may be

made of considerable length in proportion to its diameter, whereby the heat is utilized to the best advantage, inasmuch as a long thin body or heap of work-metal is more accessible to the heat and more readily melted, and a relatively long metal crucible of relatively small diameter is more efficient in melting the work-metal than is the standard relatively short metal pot of great diameter. The metal bottle has the advantage that it is not 45 apt to amalgamate with the copper or the zinc of which the brass is formed.

The metal pot or crucible is preferably given the form of a bottle, and can be mounted for tilting, and it can be rotated on its 50 longitudinal axis, and gas flames may be arranged to play upon the bottle as it rotates. Then it may be turned upon its trunnions to decant the melted brass; the crucible or bottle being mounted in a gas-furnace to tilt therewith, under the control of the operator. The herein-described bottle may survive about 55 twice as many heatings as an ordinary graphite pot; and when worn out it may be readily detached from its mountings and replaced by 60 a fresh bottle.

The same crucible, because of its constant revolution, may economically melt either a 65 large or a small quantity of brass. The invention is very flexible in meeting the different practical requirements, as compared with a graphite melting pot of standard manufacture.

The metal bottle is heated by means of a 70 flame of mixed fuel-gas and compressed air, which is advantageously applied to the top portion of the revolving bottle, and substantial reduction in the cost of brass melting is effected, as compared with standard practice.

75 Thus a metal crucible may be employed in the form of a revolving pot or bottle, having a high degree of conductivity, as compared with standard graphite crucibles. This economy is rendered practicable by the rotation of the crucible, since the flame does not impinge long enough against one point of the revolving bottle to melt or soften the same. This solves the problem of supplying 80 heat to melt brass without melting the metal pot. While the revolution of the crucible 85

prevents the same from being exposed to the flame long enough at any one point to injure it, still it absorbs as much heat as is required, and imparts said heat to the brass work.

5 The crucible may be prevented from internal oxidizing, and air or injurious gases cannot come in contact with the work, because the crucible is sealed. Internal pressure may be generated, which will raise the boiling 10 point of the melting brass, without raising the melting point thereof; that is, the pressure of the gas upon the work will be such that the vaporization point of zinc will be raised. The crucible is sealed at its mouth 15 so as to retain the volatilized zinc under pressure.

It is further sought by the present invention to facilitate the charging of a crucible, and to facilitate, quicken and cheapen the 20 melting of brass to bring the heat during the whole operation under better control than has heretofore been found practicable, and to overcome other difficulties in brass melting.

There must be an element used in the furnace as part of a heat-regulating device, as the furnace must be guarded very carefully against overheating, which would result in the melting of the pot. The element is put 25 into the bottom of the furnace below the retort where the flame cannot touch it. The difference is very slight between the melting point of the pot and the point to which the melted brass has to be heated.

30 Preferably the crucible is in the form of a cast bottle formed of an alloy consisting of iron and chromium. This bottle has a bottom or closed end from which extends a stem or hub which is cast integral with the bottle, and is of small diameter, and projects 35 through the wall of the furnace. By reason of its small dimensions it wastes very little heat by radiation outside of the furnace. Moreover, it permits the use of a small hole 40 in the furnace-wall so as to avoid loss of heat through the crevice in which the stem revolves.

The bottle is made relatively thin and long, say 9 inches in diameter and 3 or 4 feet long.

50 At the other end the bottle is reduced in diameter and formed with a neck and mouth, the diameter of the neck being about 6 inches and extending through a hole in the opposite wall of the furnace.

55 In the furnace is provided a removable section containing the hole through which the bottle-neck projects. This collar is removable, to permit withdrawal of the bottle from the furnace.

60 Other features and advantages will hereinafter appear.

In the accompanying drawings,

Figure 1 is a sectional longitudinal elevation of the preferred form of carrying out the invention, a level working position of the

melting bottle being shown by full lines, and a tilted position in dot-and-dash lines. The bottle may be decanted downwardly to discharge the melted brass.

Figure 2 is an elevation of the driving end 70 of the furnace.

Figure 3 is a section through line 3—3 of Figure 1, showing the arrangement of the melting bottle in the furnace, and the preferred arrangement of burners, and also 75 showing the element of the pyrometer.

Figure 4 is a plan of the furnace and appurtenances, partly in section.

80 A cylindrical furnace 10 is journaled between its ends by means of gudgeons 11 upon a supporting framework 12. A heating chamber 13 extends from end to end of the furnace, and contains a brass-melting pot, preferably in the form of a bottle 14 which revolves within the chamber 13. The bottle 85 may be of cylindrical form and occupy a position near the bottom of the heating chamber, in the top of which may be placed oppositely directed burners 15 for mixed gas and compressed air, as seen in Figure 3, the flames impinging upon the top of the melting bottle, which, because of its continuous revolution, does not at any place remain exposed to the pre-heating of the flame very long, and therefore does not soften nor melt. 95

90 By reason of the revolution, the pre-heated portion of the bottle revolves from top to bottom, where it comes in contact with the work in the bottle. The work absorbs the heat from the wall of the bottle and no part 100 of the bottle is pre-heated much above the brass-melting point, and hence the bottle remains intact. The heating may be effected by other combustibles, or by an electric heating furnace equipment.

105 The bottle is supported for revolution outside of the ends of the furnace on rolls 16, 17 at one end, and 18, 19 at the other end. The closed end of the bottle may be spheroidal or dome-like, as at 20, and from this end 110 projects a stem or gudgeon 21 through a small opening 22 in the end wall 23 of the furnace. This stem 21 terminates in a reduced axle-portion 24, upon which is fixed a hub 25, having a circular tread 26 to ride 115 upon the rolls 16, 17; a driving sprocket 27 being secured to this hub for rotating the bottle. The diameter of the hole 22 is only very slightly larger than the diameter of the stem 21, so as to minimize the waste of 120 heat from the furnace.

125 The other end of the bottle is reduced at 28, and is formed with a neck in the form of a hollow trunnion 29, which projects through the end of the furnace and rides 130 directly upon the supporting rolls 18, 19.

130 In order to charge the melting bottle, the furnace may be tilted up, thereby raising the mouth 30 to work-receiving position. Thereupon the bottle may be lowered to the desired

position, and heated by burning a mixture of gas and air delivered from the burners 15. If only a small quantity of brass is being melted, the bottle may maintain a horizontal position, as at Figure 1, since the reduced end or shoulder 28 of the bottle will permit the body to retain a considerable volume of melted brass; this shoulder confining the brass to the body-portion of the bottle, which is within the heating chamber of the furnace.

During the melting, the crucible-heating flames flow in opposite transverse directions from the burners across the top and down around the sides of the bottle; and the supply of fuel is controlled, so that the crucible or bottle will be exposed to no more heat than can be readily taken up by the melting brass, so as to avoid undue heating and therefore and possibility of softening or melting 20 of the bottle itself before its heat can be imparted to the work. The bottle being placed in the lower part of the furnace, Figure 3, receives most of the heat at its top portion, and its temperature is lowered as the bottle revolves and the heated part comes in contact with the brass, which is indicated at 31.

The bottle, with the stem 21, axle-portion 24, neck 29 and mouthing 30, consists of one piece or a single casting. The bottle or crucible is made of an alloy which successfully resists the superheat to which it is necessary to raise the melted brass after it has been melted, before it can be poured successfully. This alloy consists of iron and chromium. 35 The proportions are about 65% iron and 35% chromium. The iron is .65 carbon. For melting some alloys, the crucible may be made at 65% iron, 27% chromium and 8% nickel. The melting point of the crucible is about 40 2400° or a little more, which is sufficiently high for practical purposes above the heat of 2200° to which the melted brass must be superheated before pouring. The melting point of brass is 1900°, but the melted brass

45 has to be superheated up to 2100°, so that it can be poured successfully into moulds, because it is too sluggish for that purpose when it is barely melted. Sometimes the heat of the melted mass runs up to 2200°, 50 or within 200° of melting the crucible itself. The difference is very slight between the melting point of the crucible and the highest point to which it is necessary to melt the brass in order to pour it.

55 It will be understood that the use of a metal pot for brass melting has not heretofore been found feasible, because the brass has to be superheated after melting, and consequently the metal pot itself would be apt to 60 soften and melt from the heat; the melting point of the metal pot being only a trifle higher than the point to which it is necessary to superheat the melted brass. It is moreover impracticable to guard against over-heating a metal pot, under the circumstances.

In addition, the metal of the pot would be apt to amalgamate with the brass, or with one of the constituents of the brass; and the amalgamation of the pot with the brass would lower the melting point of the pot itself, so that melting of the material of the metal pot would be practically unavoidable.

70 It will be perceived that these difficulties have been overcome by the present invention. One of the important features of the invention is the provision of means whereby the metal pot or crucible can be safeguarded against melting. To this end the heat is supplied to the pot or crucible at a point remote from the point where the brass is being melted, and a pyrometer element is inserted in the furnace at a point remote from the point where the flames are generated. The pyrometer tells what is the heat in the furnace-chamber at that remote point, which information is found practically sufficient for the purpose of regulating the heat of the crucible to keep it below the softening point. This heat control is rendered feasible by continually revolving the crucible, so that the portion thereof that is pre-heated by the flames is slowly brought into contact with the brass, which is gradually melted and superheated.

75 The chromium does not amalgamate with the zinc nor the copper, nor does the iron. This alloy has sufficient strength so that when the bottle is raised to the desired brass-melting heat, it will be self-supporting and maintain its form, and not be liable to soften 80 so long as the bottle is revolving. This bottle is capable of use for about one hundred and sixty melting operations as compared with about seventy for ordinary graphite crucibles. The metal has quite high conductivity, in that it readily absorbs the heat from the furnace, and readily imparts the same to the brass-work.

85 The stem on the bottom of the bottle is to save the heat. It reduces the extent to which heat is wasted by radiation outside of the furnace, and permits the use of a small hole in the furnace-wall. The bottle has great length and small diameter, to expose the melting brass advantageously to the attack 90 of heat. There is but little liability of bending of the heated crucible or bottle. The rotation of the bottle prevents the flame from overheating and softening and perhaps melting, all of which might occur if the bottle 95 were kept stationary, especially if flames were applied to the top thereof, as shown. The stem is three inches in diameter. The neck of the bottle is 6 inches in diameter.

100 It will be seen that a great saving of fuel 105 is effected by reducing both projecting ends of the bottle, so as to reduce correspondingly the holes in the furnace-walls, and have the neck of the bottle only large enough to permit the charging.

After the work is in place, a cover 32 is fastened tightly on the mouth 30 of the bottle by means of hooks 33, catching under a rim 34 and being tightened by thumb-nuts 35, so that the bottle is made sufficiently gas-tight to permit the volatilized zinc therein to rise to considerable pressure above atmospheric, thereby raising the boiling point of the metal, and tending to reduce loss of volatile constituents. To the cover may be connected a pipe 36 for supplying an inert gas under pressure to the bottle in some cases.

The furnace and crucible may maintain a level position, as at Figure 1, or be swung to an upwardly-inclined position, according to the quantity of work in the bottle. The inclined bottle holds more work. The tilting of the furnace is effected by a crank 37, driving bevel gears 38, 39, the latter operating a worm 40, which turns a worm-wheel 41 provided upon one of the furnace-gudgeons 11.

The bottle 14 is given a slow revolution by means of a motor 42, having a drive-chain connection to a movement-reducing chest 43, the delivery shaft 44 of which rotates slowly. Upon the shaft 44 is a bevel pinion 45, meshing with a pinion 46 upon a shaft 47, which carries a sprocket 48, connected by a chain 49 to the sprocket 27 upon the axle 24 of the work bottle or crucible.

The bottle turns upon the rolls 16—19, and when the furnace is tilted up, the weight of the work bottle or crucible is partly supported by means of a bearing provided in an arm 50 secured by bolts 51 on the wall of the furnace. To relieve friction, there is provided a circular row of bearing balls 52, which run in grooves formed in a pair of washers or collars 53 which are placed upon a nipple 54, projecting from the end of the bottle-axle 24.

The crucible is kept from melting by the aid of a heat-regulating device which includes a pyrometer having an element 55^a extending through an orifice 56 through the wall of the furnace, and terminating in the bottom part of the flame-chamber where the heat is least. After the melted metal has been heated to the proper point for pouring, the flames are shut off, and the crank 37 is revolved to rock the furnace down to decanting position, the cap 32 having been removed.

The shoulders 28 enable the bottle to retain a fair quantity of melted metal while the bottle is in level position, but the furnace does not have to be tilted down very much in order to discharge the entire contents of the bottle. The neck 57 of the bottle is flared outwardly or cone-shaped, for convenience in both charging and discharging the bottle, and for realizing other advantages.

When the furnace is tilted down, the bottle is retained in position by means of a flange 58, that is formed on the hub 25 on the bottle-axle; this flange overhanging the rolls 16,

17 and holding the bottle against slipping when decanting.

When it is desired to remove the crucible, a section of the furnace-wall may be removed, leaving an opening large enough for taking out and replacing the crucible, or substituting a new one. This removable section is in the form of an annulus 59, filling a circular opening 60 in the end of the furnace, Figure 1. This annular section is only a trifle larger than the bottle-neck, so as to minimize the waste of heat from the furnace. To the same end, the opening 60 is provided with a stepped series of shoulders 61, and the furnace-wall is provided with corresponding steps, thereby overcoming waste of heat through the joint between the annular section and the furnace-wall itself. If the section 59 is made too small to slip over the brim 34 on the end of the bottle-neck, the section may be made in segmental halves, which may be secured together to form a complete collar or annular section. The brim 34 of the bottle-neck may, however, be made so small as to permit the collar 59 to be made in one piece and slipped over the brim. This section or collar may be of heat-resisting material, of a character used in building furnaces. The collar may be held in place by a series of buttons 62 loosely bolted at 63 to the iron-facing frame 64 of the furnace-end.

The use of very close apertures in the furnace-ends is permitted, by reason of the expedient of adjusting the crucible at each end independently, so as to bring it to a true central position within the apertures 22 and 65. This adjustment is effected by means of set-screws 66, 67, Figure 2, threaded through lugs 68 formed in the end walls of the furnace. These set-screws support the upper ends of levers 69, 70 pivoted at 71 to the bottom of the furnace, and provided with studs 72 upon which the rolls 16—19 rotate. The levers 69, 70 diverge upwardly and outwardly, so that if either set-screw is unscrewed, the levers 69 or 70 will fall outwardly to a corresponding extent, together with the rolls 16 or 17, thereby lowering one end of the work-bottle. By screwing up the set-screws, the rolls may be raised one at a time. This gives universal adjustment of each end of the bottle up or down and to the right or left, at Figure 2. This readjustment is a special convenience when replacing a worn out bottle with a new one, as the new bottle is very readily centered.

There is quick replacement without taking down the furnace. It is only necessary to take out the collar and take off a driving wheel. The furnace may include iron end frame or wall 64, and an iron frame 73 for the opposite end, these end walls being joined by a cylindrical metal shell or body 74, attached to the ends by annular devices 75. The shell 74 has a lining of asbestos 76, surrounding blocks which form a tubular body 130

77 of suitable heat-retaining substance. Within the tubular body 77 is supported the firebrick body 78 of the furnace, having holes 79 for the burners 15, and having at its ends the opening 22 for the stem 21 of the work-bottle, and having in the other end the circular-stepped opening 60, 61 for the removable annular section 59. The left-hand end of the furnace, Figure 1, may be provided with a sight-hole 80.

It is often necessary, in producing a furnace, to trim off the ends of the furnace-body 78, so that it will fit between the iron end-frames 64, 73. To overcome this difficulty, 15 the furnace-body 78 is made under-length, and the discrepancy is made up by the use of packing disks or annular sheets 81 of asbestos, which readily close the gaps between the ends of the furnace-body 78 and the iron frames 20 or ends 64, 73. This affords provision for a certain range of variation in the length of the body or lining, and in the length of the furnace. The asbestos can be in sheets of $\frac{1}{8}$ to $\frac{1}{4}$ inch thickness, and may be packed in as required, to fill up the end spaces. These asbestos sheets make the ends tight, as both thin and thick ones may be packed in as required, and no labor is required for trimming off the end of the furnace-body or lining 78.

30 In view of the exposure of the crucible to liability of melting under the high heat which is necessary, there is provided in the bottom of the furnace a large outlet 82, so that melted metal falling into the furnace 35 may escape into a suitable receptacle that may be provided beneath the outlet 82, and thereby avoid or minimize the damage which the hot metal might effect.

Variations may be resorted to within the 40 scope of the invention, and portions of the improvements may be used without others.

Having thus described my invention, I claim:

1. A brass-melter including a liquid-tight 45 one-piece crucible in the form of a cumbent shouldered metal bottle, a furnace through which the ends of the metal bottle protrude, means exterior to the furnace upon which the bottle is mounted for revolution, means for 50 heating the bottle, means for tilting the furnace and bottle up or down, said bottle formed of the desired alloy which does not amalgamate with brass and whose melting point is higher than the point to which the 55 brass is superheated preparatory to pouring the same out of the bottle, means for heating the top portion of the metal bottle while the work is confined by the shoulder in the lower part of the cumbent bottle, means for slowly 60 revolving the bottle on its longitudinal axis, and means for sealing the bottle, whereby pressure may generate within the bottle to raise the boiling point of the melted metal.

2. Apparatus constructed according to 65 claim 1, in which the sealing means includes

a cover for the bottle, and means for fastening the cover to the bottle, said cover having a pipe for supplying inert gas to the bottle.

3. A brass-melting crucible in the form of a revoluble liquid-tight one-piece cast bottle formed of an alloy of iron and chromium, the melting point of the crucible being about 2400°, the proportions being substantially 65% iron and 35% chromium, and having at one end a shoulder terminating in a neck, the shoulder co-operating with the bottom of the bottle and with the under side of the bottle to form a melting pot during the revolution of the bottle when in cumbent position; said bottle having at its opposite end an integral gudgeon co-operative with the neck of the bottle to mount the bottle for rotation.

4. A brass-melting crucible in the form of a revoluble liquid-tight one-piece cast bottle formed of an alloy of iron and chromium, the melting point of the crucible being about 2400°, the proportions being substantially 65% iron and 35% chromium, and having at one end a shoulder terminating in a neck, the shoulder co-operating with the bottom of the bottle and with the under side of the bottom to form a melting pot during the revolution of the bottle when in cumbent position.

5. A brass-melting crucible in the form of a revoluble liquid-tight one-piece cast bottle formed of an alloy of iron and chromium, the melting point of the crucible being about 2400°, the proportions being substantially 65% iron and 35% chromium, said bottle being of a length of 3 or 4 feet, and a diameter of about 9 inches and having at one end a shoulder terminating in a neck, the shoulder co-operating with the bottom of the bottle and with the underside of the bottle to form a melting pot during the revolution of the bottle when in cumbent position.

6. A brass-melting crucible in the form of a cumbent liquid-tight one-piece cast bottle formed of the specified alloy of iron and chromium, the melting point of the crucible being about 2400°, the bottle not scaling off when exposed to brass-melting heat, and a perforated furnace enclosing said bottle, said bottle having an integral bottom or closed end and an integral gudgeon in the form of a hub protruding from said bottom to the exterior of the furnace and there provided with a hub-portion, rolls provided upon the exterior of the furnace for supporting said hub-portion, said hub filling closely the perforation in the wall of the furnace, and being about 3 inches in diameter and said bottle having at its opposite end a shoulder and a reduced neck, said neck about 6 inches in diameter, the furnace having a hole in its wall to fit closely about the neck of the bottle, and rolls on the outer side of the furnace to enable said neck partially to support the

bottle, the shoulder and bottom enabling the bottle to serve as a melting pot.

7. A crucible in the form of a cast bottle, and a perforated furnace enclosing said bottle, said bottle having an integral bottom or closed end and an integral gudgeon in the form of a stem or hub protruding from said bottom to the exterior of the furnace and provided with a hub portion, rolls provided 5 upon the exterior of the furnace for supporting said hub-portion, said hub being of very small diameter and fitting closely in the perforation in the wall of the furnace, said bottle having at one end a shoulder and 10 a neck, the latter protruding from the furnace and there supported on exterior rolls, said furnace having a removable section fitting about the neck of the bottle, to be removed to leave a space for removing the 15 bottle, and means for fastening the section in place in the furnace.

8. A brass-melting apparatus including a furnace mounted for tilting up or down and having perforations in its opposite ends, a 25 one-piece liquid-tight brass-melting crucible of substantially the described alloy, having a higher melting point than brass and not scaling off when subjected to brass-melting heat, and in the form of a metal bottle within the 30 furnace and having gudgeons projecting through said perforations and filling the same closely to minimize waste of heat, exterior rolls upon the furnace-walls to support said gudgeons for rotation, one of said 35 gudgeons being hollow and forming the neck of the bottle, the latter having a shoulder at said neck, to enable the bottle to operate as a melting pot when cumbent, said furnace having means for heating said bottle at 40 a section remote from the work, and means outside of the furnace for rotating said bottle.

9. A brass-melting one-piece crucible in the form of a cast bottle formed of an alloy 45 of iron, chromium and nickel, not amalgamating with melted brass, or scaling off when exposed to heat sufficient to melt brass, the melting point of the crucible being about 2400°, the proportions being substantially 50 65% iron, 27% chromium and 8% nickel, said bottle having means for supporting it by its ends for revolution in cumbent position, and for decanting, one end of the bottle having a discharge neck and a shoulder to confine the melted work in the revolving 55 cumbent bottle.

10. A metal-melting apparatus including a furnace mounted for tilting up or down and having perforations in its opposite ends, 60 a crucible in the form of a liquid-tight metal bottle within the furnace and having gudgeons of greatly reduced diameter projecting through said perforations and filling the same closely to minimize waste of heat, rolls 65 upon the exterior of the furnace-walls to

support said gudgeons for rotation, one of said gudgeons being hollow and forming the neck of the bottle, said furnace having means for heating said bottle, and means outside of the furnace for rotating said bottle, said 70 bottle being provided with a shoulder at the base of said neck for enabling a quantity of melted metal to be retained in the bottle to enable it to serve as a melting pot while it is in level position, the neck of the bottle being flared outwardly from its base to its discharge end. 75

11. A brass-melting crucible in the form of a cast bottle formed of an alloy of iron and chromium, the melting point of the crucible being about 2400°, a perforated furnace enclosing said bottle, said bottle having an integral bottom and an integral gudgeon in the form of a stem protruding from said bottom to the exterior of the furnace and provided with a hub-portion, rolls 80 provided upon the furnace for supporting said hub-portion, said hub being of very small diameter and fitting closely in the perforation in the wall of the furnace, said bottle having a neck protruding from the furnace and supported on exterior rolls, said furnace having a removable section fitting about the neck of the bottle, and means 85 for fastening the section in place in the furnace, said removable section in the form of an annulus, and the furnace-wall having a circular opening in which the annulus is fitted; said annulus having a stepped series of annular shoulders, and the furnace-wall provided with corresponding stepped annular seats, to avoid waste of heat through the joint; said fastening means including a series of buttons 90 loosely holding the section in place in the furnace. 95

12. A brass-melting apparatus including a furnace mounted for tilting up or down and having perforations in its opposite ends, a brass-melting crucible in the form of a metal 100 bottle within the furnace and having gudgeons projecting through said perforations and filling the same closely to minimize waste of heat, exterior rolls upon the furnace-walls to support said gudgeons for rotation, one of said 105 gudgeons being hollow and forming the neck of the bottle, said furnace having means for heating said bottle, means outside of the furnace for rotating said bottle, and centering means outside of the furnace for adjusting the crucible at each end up or down, and also sidewise, independently of the other end, 110 so as to bring the crucible to a true central position within the closely fitting apertures in the furnace-walls, said centering means including set-screws provided in lugs in the end walls of the furnace, and levers being mounted at the outside of each end of the furnace and pivotally supported, and having means whereon the bottle-supporting rolls rotate, said levers being adjustable by means of said 115 120 125 130

set-screws, and diverging upwardly and outwardly so that by manipulating the screws the positions of the levers may be changed independently of one another, and the position of the bottle thereby corrected.

13. A furnace in which is mounted a revoluble work-containing member which extends through the ends of the furnace and is provided outside the furnace with supporting and rotating means, said furnace including iron end frames, a cylindrical metal shell joining said end frames and attached thereto, gudgeons upon said shell for tilting the furnace, said shell lined with heat-retaining substance, a tubular body of fire-brick which is surrounded by said lining of heat-retaining substance, said body formed with ends having holes through which said work-containing member protrudes, said furnace-body being made under-length, and packing disks of asbestos closing the spaces between the ends of the under-length body and the iron end frames of the furnace.

14. A brass-melting crucible in the form of a cast bottle formed of an alloy of iron and chromium, the melting point of the crucible being about 2400°, a perforated furnace enclosing said bottle, said bottle having an integral bottom and an integral gudgeon in the form of a stem protruding from said bottom to the exterior of the furnace and provided with a hub-portion, rolls provided upon the furnace for supporting said hub-portion, said hub being of very small diameter and fitting closely in the perforation in the wall of the furnace, said bottle having a neck protruding from the furnace and supported on exterior rolls, said furnace having a removable section fitting about the neck of the bottle, and means for fastening the section in place in the furnace, said removable section in the form of an annulus, and the furnace-wall having a circular opening in which the annulus is fitted.

15. A brass-melting crucible in the form of a cast bottle formed of an alloy of iron and chromium, the melting point of the crucible being about 2400°, a perforated furnace enclosing said bottle, said bottle having an integral bottom and an integral gudgeon in the form of a stem protruding from said bottom to the exterior of the furnace and provided with a hub-portion, rolls provided upon the furnace for supporting said hub-portion, said hub being of very small diameter and fitting closely in the perforation in the wall of the furnace, said bottle having a neck protruding from the furnace and supported on exterior rolls, said furnace having a removable section fitting about the neck of the bottle, and means for fastening the section in place in the furnace, said removable section in the form of an annulus, and the furnace-wall having a circular opening in which the annulus is fitted; said annulus having a

stepped series of annular shoulders, and the furnace-wall provided with corresponding stepped annular seats, to avoid waste of heat through the joint.

16. A metal-heating apparatus including a furnace mounted for tilting up or down and having perforations in its opposite ends, a work-receptacle liquid-tight within the furnace and having gudgeons projecting through said perforations and filling the same closely to minimize waste of heat, exterior rolls upon the furnace-walls to support said gudgeons for rotation, one of said gudgeons being hollow and forming the neck of the receptacle, said furnace having means for heating said receptacle, means outside of the furnace for rotating said receptacle, and centering means outside of the furnace for adjusting the receptacle at each end up or down, and also sidewise, independently of the other end, so as to bring the receptacle to a true central position within the closely fitting apertures in the furnace-walls, said centering means including set-screws provided in lugs in the end walls of the furnace, and levers being mounted at the outside of each end of the furnace and pivotally supported, and having means whereon the receptacle-supporting rolls rotate, said levers being adjustable by means of said set-screws, and diverging upwardly and outwardly so that by manipulating the screws the positions of the levers may be changed independently of one another, and the position of the receptacle thereby corrected.

ADOLPH W. MACHLET.
